[57] CLAIM

The ornamental design for a computer for composing music, as shown and described.

DESCRIPTION

FIG. 1 is a front, top and side perspective view of the computer for composing music embodying the design of the present invention;

FIG. 2 is a front elevational view thereof on an enlarged scale;

FIG. 3 is a rear elevational view thereof;

FIG. 4 is a side elevational view thereof;

FIG. 5 is an opposite side elevational view thereof;

FIG. 6 is a top plan view thereof; and,

FIG. 7 is a bottom plan view thereof.

FIG.1.

FIG.6.

FIG.2.

FIG.3.

FIG.5.

FIG. 7.

FIG. 4.
